EXPLOSIVE RIVET

Anton Widrich, Eatontown, N. J.

Application February 25, 1944, Serial No. 523,783

3 Claims. (Cl. 85—37)

This invention relates to new and useful improvements in an explosive rivet.

More specifically, the invention proposes the construction of an explosive rivet employing an explosive charge to rivet the rivet in place and eliminate necessity of using hammers, and which may be inserted into an opening of parts to be riveted and hit upon the head to explode said charge and cause the free end of its shank portion to be expanded on the other side of the material to which the rivet is applied, permitting the rivet to be used in small spaces without requiring that it be backed up during its insertion period.

A further object of the invention proposes providing the interior of the shank portion of the rivet with a chamber within which an explosive charge is disposed to be exploded by hitting the rivet on the head with a hammer or other heavy object to set off a detonating cap and explode said charge.

Still another object of the invention proposes providing the head of the rivet with a blister-like protuberance within which the detonating means may be mounted for setting off the charge when the head of the rivet is hit to collapse said protuberance.

A still further object of the invention proposes the provision of novel means for connecting the interior of the protuberance with the charge and being mounted in the shank portion of the rivet to insure exploding the charge when the rivet is hit.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of an explosive rivet constructed in accordance with this invention and shown in position within openings in pieces of material to which the rivet is to be applied.

Fig. 2 is a view similar to Fig. 1 partly in vertical section and illustrating the rivet after being exploded.

Fig. 3 is a vertical sectional view of the rivet, per se, before explosion.

Fig. 4 is a bottom view looking in the direction of the line 4—4 of Fig. 3.

Fig. 5 is a sectional view similar to Fig. 3 but illustrating a modification of the invention.

Fig. 6 is still another sectional view similar to Fig. 3 but illustrating a further modification of the invention.

Fig. 7 is a vertical sectional view of an explosive rivet constructed in accordance with a still another modification of the invention.

Fig. 8 is a plan view of the rivet shown in Fig. 7.

The explosive rivet, according to this invention, includes a rivet body 10 having a head portion 11 and a shank portion 12 formed with an internal chamber 13. The top of the head 11 of said rivet body is formed with a blister-like protuberance 14 which is hollow and which is connected by means of a channel 15 with the interior of the chamber 13 formed in the bottom of the shank 12 of said rivet body.

An explosive charge 16 is mounted within the chamber 13 and a detonating means is provided for connecting the interior of the blister-like protuberance 14, and the channel 15 with the charge 16 to cause the charge to be exploded when the head portion 11 of the rivet 10 is hit with a hammer or other hard object, collapsing the protuberance 14. This detonating means includes a cap 17 mounted within the protuberance 14 and connected by ignitable material 18 with the charge 16 in the chamber 13. The ignitable material 18 is mounted within the channel 15 and might be gun powder or other similar material which will burn down through the channel 15 to chamber 13.

The bottom of the shank portion 12 of the rivet body 10 is provided with a plurality of radiating slots 19 for facilitating opening the bottom portion of the shank 12 under the influence of the pressure set up by the exploding charge 16.

The manner of using the explosive rivet, constructed according to this invention, is as follows:

The shank portion 12 of the rivet body 10 is projected into openings in the materials M to which the rivet is applied. The head of the rivet 11 is then given a smart crack with a hammer or other similar object causing the protuberance 14 to be collapsed. This will explode the cap 17 and light the ignitable material 18 in the channel 15 causing it to burn downwards into the chamber 13 and explode the charge 16. The pressure set up by the exploding charge 16 will spread the bottom end of the shank of the rivet, as permitted by the slots 19, to assume the position shown in Fig. 2 and prevent the rivet from

being withdrawn through the opening in the materials M to which the rivet is applied.

It will be noted that the use of the explosive charge within the rivet body 10 eliminates the use of hammers for flattening the shank end of the rivet and also permits the rivet to be used in limited spaces where it would be impossible to back up the rivet during the time that the hammer is being used for flattening the shank end thereof.

In the modified form of the invention disclosed in Fig. 5 the detonating unit is a separate unit from the rivet body. It is merely placed into the rivet body contrasted with the prior form in which it was actually built in. In this form the detonating cap 17', the fuse material 18', and the charge 16' are a complete unit. They are placed into the rivet body during manufacture thereof.

In other respects this form of the invention is similar to that previously shown and like reference numerals identify like parts in each of the several views.

In the modification of the invention shown in Fig. 6 the construction of the explosive rivet is similar to that previously described, except that the cap 17a is mounted directly on the top of the explosive charge 16a contained within the chamber 13a. The channel 15a frictionally supports a firing pin 20 which has its top end projected into the hollow of the protuberance 14a. Thus when the rivet in this form of the invention is struck upon the head, the protuberance 14a will be collapsed causing the firing pin 20 to be forced downwards within the chamber 15a to strike the cap 17a and set off the explosive charge 16a contained within the chamber 13a.

In other respects this form of the invention is similar to that previously shown and like reference numerals identify like parts in each of the several views.

In Figs. 7 and 8 still another form of the invention has been disclosed which is very similar to the first form of the invention, distinguishing in the fact that the protuberance 14b is formed from material separate from the material of the rivet head 11, and is permanently mounted in position on the rivet head. The protuberance 14b is shown of disc shape and set into a complementary circular recess 30 formed in the top of the rivet head 11. This member 14b preferably is welded, braised, or in any other suitable manner fixedly mounted in place. The protuberance 14b has a hollow portion 31 into which the cap 17b of the detonating unit engages.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

10. 1. An explosive rivet having a rivet body formed with a head portion and a shank portion formed with an internal chamber housing an explosive charge and continuing into a channel extending axially through said shank portion to the head portion, a detonating cap in said passage and projecting slightly above said head portion for exploding said charge when said head portion is hit with a hammer or the like, and means for protecting the projecting portion of the detonating cap against a premature blow accidentally setting off the explosive charge.
15. 2. An explosive rivet having a rivet body formed with a head portion and a shank portion formed with an internal chamber housing an explosive charge and continuing into a channel extending axially through said shank portion to the head portion, a detonating cap in said passage and projecting slightly above said head portion for exploding said charge when said head portion is hit with a hammer or the like, and means for protecting the projecting portion of the detonating cap against a premature blow accidentally setting off the explosive charge, comprising a collapsible blister-like protuberance formed on the top of said cap and enclosing the projecting portion of said detonating cap.
20. 3. An explosive rivet having a rivet body formed with a head portion and a shank portion formed with an internal chamber housing an explosive charge and continuing into a channel extending axially through said shank portion to the head portion, a detonating cap in said passage and projecting slightly above said head portion for exploding said charge when said head portion is hit with a hammer or the like, and means for protecting the projecting portion of the detonating cap against a premature blow accidentally setting off the explosive charge, comprising a collapsible blister-like protuberance formed on the top of said cap and enclosing the projecting portion of said detonating cap.
25. 4. An explosive rivet having a rivet body formed with a head portion and a shank portion formed with an internal chamber housing an explosive charge and continuing into a channel extending axially through said shank portion to the head portion, a detonating cap in said passage and projecting slightly above said head portion for exploding said charge when said head portion is hit with a hammer or the like, and means for protecting the projecting portion of the detonating cap against a premature blow accidentally setting off the explosive charge, comprising a collapsible blister-like protuberance formed on the top of said cap and enclosing the projecting portion of said detonating cap.
30. 5. An explosive rivet having a rivet body formed with a head portion and a shank portion formed with an internal chamber housing an explosive charge and continuing into a channel extending axially through said shank portion to the head portion, a detonating cap in said passage and projecting slightly above said head portion for exploding said charge when said head portion is hit with a hammer or the like, and means for protecting the projecting portion of the detonating cap against a premature blow accidentally setting off the explosive charge, comprising a collapsible blister-like protuberance formed on the top of said cap and enclosing the projecting portion of said detonating cap, said protuberance having its inner face out of contact with the projected end of said detonating cap requiring a smart blow to actually collapse said protuberance to set off said cap.

ANTON WIDRICH.
